UNITED STATES PATENT OFFICE

139,430

DESIGN FOR A DICKEY OR SIMILAR ARTICLE

David Rothman, New York, N. Y.

Application September 1, 1944, Serial No. 115,162

Term of patent 3½ years

(Cl. D3—25)

To all whom it may concern:

Be it known that I, David Rothman, a citizen of the United States of America, residing in New York city, county of New York, and State of New York, have invented a new, original, and ornamental design for a Dickey or Similar Article, of which the following is a specification, reference being had to the accompanying drawing, forming part thereof, wherein,

I claim:

The ornamental design for a dickey or similar article, substantially as shown.

DAVID ROTHMAN.
